UNITED STATES PATENT OFFICE

2,481,625

AIR-CONDITIONING UNIT

Thomas H. Sarchet, Spokane, Wash.

Application August 29, 1947, Serial No. 771,310

2 Claims. (Cl. 257—3)

1

This invention relates to air-conditioning units, and more particularly to an air conditioner which may be built into the wall of a house.

It is an object of the present invention to provide a combined heating radiator and humidifier which can be contained within the wall of a room to economize on floor space and wherein the unit further contains fan elements for causing the circulation of the air through the unit.

It is another object of the present invention to provide in a combined heating and humidifier unit an arrangement wherein water may be dropped or ejected with a fine spray on the surface of the radiator to humidify the air being circulated through the unit.

It is another object of the present invention to provide in a combined air-conditioning and heating unit a common drain for cooling water that may be sprayed over the radiator surface when the apparatus is used for cooling when the steam is turned off, the water being returned to the sewer system.

For other objects and for a better understanding of the invention, reference may be had to the following detailed description taken in connection with the accompanying drawings, in which:

Figure 1 is a front elevational view of the air-conditioning unit with the door of the housing opened up to show the interior of the housing and the elements disposed therewithin.

Figure 2 is a longitudinal cross-sectional view taken on line 2—2 of Figure 1 and looking in the direction of the arrows thereof.

Figure 3 is a transverse cross-sectional view taken on line 3—3 of Figure 1, and looking in the direction of the arrows thereof, and upon the fans disposed in the top of the housing.

Figure 4 is a view showing a method of applying the air-conditioning heating and humidifying unit to steam and hot water radiators of heating systems now in use.

Referring now to the figures, 10 represents a housing or casing adapted to be disposed in a wall so that its front portion will lie flush with the interior wall surface and so that no floor space is consumed. The housing may also be portable and adapted to be used as a separate complete unit. On this housing is a door 11 adapted to swing on hinges 12 and 13 to the open position shown in Figure 1. Within this casing 10 is a steam radiator 14 having an inlet pipe 15 and an outlet pipe 16. A steam main 17 extends vertically through the wall and leads to the inlet for delivery of steam to the steam ra-

diator 14. The inlet 15 is controlled by a valve 18. The inlet includes a union 19. On the outlet 16 at the bottom of the radiator is a radiator trap 21 having a down pipe 22 connected with a radiator drain pipe 23. At the bottom of the housing is a pan 24 adapted to catch water which is sprayed over the radiator when the device is used for cooling. From this pan there is extended a trap 25 which is connected to a valve 26 to the same return 23 as is utilized for the condensation within the radiator.

Also extending upwardly through the wall parallel to the pipe 17 is a cold water pipe 27 for connecting water to a laterally extending spray pipe 28 within the housing. A valve 29 controls the flow of water to the spray pipe 28. The spray pipe has a plurality of longitudinally spaced openings adapted to spray water downwardly over the radiator 14. This water forms a screen and the air which is caused to pass upwardly over the radiator 14 will be cooled or moistened. The dead end of the spray pipe 28 is carried in a bracket 31 connected to one side of the casing. The water will be collected in the pan 24 at the bottom, and when the valve 26 is opened will be drained through the trap and permitted to join with the steam condensation from the radiator 14 for return to pipe 23 or to a sewer system.

The door 11 has a screened opening 33 at the bottom thereof and screened openings 34 laterally spaced from one another at the top of the door and adapted to lie in front of fans 35 mounted on brackets 36 depending from the top of the casing. These fans are driven by a motor 37 through drive chains 38. This motor 37 is also located at the top of the casing upon a bracket 39 on the inner wall of the casing.

The motor 37 is controlled by a thermostat 41 at times when the radiator 14 is being used for heating purposes. At other times when it is desired to use the unit for cooling purposes, a toggle switch 42 is thrown to cause the constant rotation of the driving motor 37. A supply cable 43 extends upwardly along the side of the casing for delivery of current to the toggle switch 42. Cables 44 connect between the toggle switch and the thermostat 41. With the door 11 closed and the fans 35 in operation, air will be drawn through the large opening 33 at the bottom of the door and upwardly over the radiator 14 and thence outwardly through the small openings 34 in the top of the door.

As seen more clearly in Figure 2, the radiator may have a plurality of baffles 45 and 46 located respectively upon opposite sides of the radiator

whereby to cause the air in flowing upwardly to take a circuitous path in and out of sections of the radiator until it finally reaches the top of the radiator. These baffles 45 and 46 extend laterally across the front of the radiator, and across the rear of the radiator.

When the room temperature reaches the correct temperature of the adjustable thermostat located in the incoming air stream beneath the radiator, or elsewhere in the room, it will automatically break the electric circuit to the fan motor and very little heat will be supplied to the room until the thermostat again sets the fan into motion, thus making it unnecessary to close the steam valve when the room maintains correct temperature.

For cooling the room temperature, the steam valve 18 is closed, the water valve 29 is opened, and the drain valve 26 is opened. This will cause the cold water to spray from the spray pipe 28 and dispose a film of water over the radiator 14. Waste water drops into the pan 24 and is drained into the return pipe 23. This water will either be returned to the heating boiler in the basement or to a sewer system, or through the boiler to a sewer drain. Air circulation through the unit is attained in the same manner as when heating, except that the thermostat will be adjusted to maintain a constant circuit and thus the fans will be manually controlled by the toggle switch 42.

The air-conditioning unit illustrated in Figures 1 to 3 constitutes a complete housing with a radiator and circulating elements therein, and in the design shown in Figure 4, a unit is provided that may be placed over a radiator of a steam or hot water heating system now in use. In this design a unique housing 47 is provided which may be made to resemble a bookcase or the like having an open area 48 at the upper end with the upper surface 49 of the housing forming a shelf. The housing is provided with a door 50 attached to the front by hinges 51 and the door is provided with screened outlet openings 52, as shown. Circulating fans 53 may be positioned behind the openings 52, and these may be rotated by belts 54 from a motor 55 that is positioned in a small protecting casing 56. The motor may be actuated by a small hand switch 57 having supply wires 58 extending thereto, or the motor may be controlled by a thermostat 59 similar to the thermostat 41 in the design shown in Figure 1, the thermostat being connected to the motor and current supply wires by wires 60. In this design the housing is placed over a radiator 61 which, in the design shown, has a supply connection 62 and return connection 63.

The housing may be provided with suitable inlet openings that may be located at convenient points and in the design shown the outer wall is provided with perforations 64 through which air may be admitted through the sides and the shelf 49 is also provided with openings 65 so that air may also pass downward from the upper end.

The air-conditioning unit of this invention may, therefore, be provided as a separate complete unit and may be located in any suitable position in a room or building, or may be built into the wall of a room or building, or the device may be provided as a skeleton housing that may be placed over a radiator of a heating system, now in use.

The apparatus may be used for heating by turning steam or hot water into the radiator and actuating the circulating fan wherein air will be circulated over the hot elements, or by turning off the

steam or hot water and supplying a spray of cold water over the radiator and circulating the air therethrough, the apparatus may be used for cooling.

Having thus described my invention, I claim:

1. A built-in air-conditioning unit comprising a casing adapted to fit into a wall, a door adapted to be extended over the casing and having openings at the bottom and top thereof, a steam radiator near the center of the casing, a steam inlet extending through the wall of the casing for connection with the steam radiator, an outlet for the steam radiator extending from the radiator to the exterior of the casing, a water inlet to the casing, a spray pipe extending over the top of the radiator and adapted to spray water downwardly thereover connected with the water inlet, a drain pan at the bottom of the radiator adapted to receive the water which passes downwardly over the radiator, an outlet for draining off the collected water in the pan, a fan arrangement including an electric motor disposed in the top of the casing above the spray pipe and radiator and adapted to cause the air within a room to be drawn inwardly through the bottom opening in the door and outwardly through the top openings thereof, switch means for controlling the supply of current to the electric motor, said radiator having laterally extending baffles on the front and rear thereof arranged respectively in staggered relation so as to cause the air in passing upwardly over the radiator to take a circuitous path in and out of laterally extending openings within the radiator until the air reaches the top thereof to be directly drawn to the fan for exit through the top openings of the door, and a thermostat connected with the switch means and motor for controlling the operation of the motor in response to the temperature of the air within the room.
2. A built-in air-conditioning unit comprising a casing adapted to fit into a wall, a door adapted to be extended over the casing and having openings at the bottom and top thereof, a steam radiator in the center of the casing, a steam inlet extending through the wall of the casing for connection with the steam radiator, an outlet for the steam radiator extending from the radiator to the exterior of the casing, a water inlet to the casing, a spray pipe extending over the top of the radiator and adapted to spray water downwardly thereover connected with the water inlet, a drain pan at the bottom of the radiator adapted to receive the water which passes downwardly over the radiator, an outlet for draining off the collected water in the pan, a fan arrangement including an electric motor disposed in the top of the casing above the spray pipe and radiator and adapted to cause the air within a room to be drawn inwardly through the bottom opening in the door and outwardly through the top openings thereof, switch means for controlling the supply of current to the electric motor, and a thermostat connected with the switch device and the motor for controlling the operation of the motor in response to the temperature of the air within the room, a valve in the inlet to the steam radiator for controlling the flow of steam thereto and adapted to be turned off at times when the radiator is not to be used, said spray pipe being adapted to pass water over the exterior of the radiator at such times when the radiator steam supply is turned off so as to cool the air being drawn over the radiator by the fan, whereby said unit is converted from a heating arrangement to a cooling arrangement, said switch being adapted to be operated to cause the

5

constant rotation of the fan when the arrangement is being used for cooling.
